UNITED STATES PATENT OFFICE.

GEORGE P. CAMPBELL, OF CINCINNATI, OHIO, ASSIGNOR OF ONE-HALF TO
JOHN O. SLOAN, OF SAME PLACE.

CAR-BRAKE.

SPECIFICATION forming part of Letters Patent No. 361,576, dated April 19, 1887.

Application filed January 24, 1887. Serial No. 225,341. (No model.)

To all whom it may concern:

Be it known that I, GEORGE P. CAMPBELL, a citizen of the United States, and a resident of Cincinnati, in the county of Hamilton and State of Ohio, have invented certain new and useful Improvements in Car-Brakes, of which the following is a specification.

This invention is an improvement upon the car-brake which is the subject of my pending application, filed August 21, 1885, Serial No. 174,939. Its objects are to simplify and cheapen the construction, render its action more sensitive and certain, and provide for the ready replacement of the frictional parts in case of wear.

In the accompanying drawings, in which like parts are uniformly marked in the various views, Figure 1 is a fragmentary view of car, upon the axle of which my improved brake-operating devices are shown in diametrical section. Fig. 2 is a view of the same, upon a larger scale, in longitudinal elevation. Fig. 3 is an end elevation of the air-cylinder with the pistons removed. The view is taken through line $\alpha\alpha$ of Fig. 2. The axle and sleeve are shown in transverse section. Fig. 4 is a transverse section through line $\alpha\alpha$, looking in the opposite direction from Fig. 3, the drum and clutch being omitted. Fig. 5 is an enlarged detail view in axial section of a modification of the air-chamber and pistons, showing one of the friction-sections made separate from the piston and secured to it by a screw; and Fig. 6 is a longitudinal elevation of the piston and section.

The sleeve A is formed in two parts to embrace and be secured to the car-axle B, and is dressed off upon the outside to form a bearing for the chain-drum C, which is also one member of a friction-clutch, and the air-cylinder D, through which the axle with sleeve A revolves, the cylinder D being held from revolving by a chain, H, one end of which is secured to the cylinder D and the opposite end to the truck-timber E. The two-part sleeve, arranged as shown, does not differ from the sleeve shown in my said former application. The chambered cylinder D is also made in two parts. The meeting edges are faced off true

to form close joints, between which a suitable 50 packing--as of thin sheet-lead, for instance--may be interposed to make the joints air-tight.

Within one end of the cylinder D is an annular air-chamber, d' , which is cored out in casting. There are four holes, d^2 , bored from 55 the opposite end of the part D, to communicate with the chamber d' . The chamber d' is in communication with the air-pump of the engine through the flexible tube d^3 , which is secured upon a nipple, d^4 . The holes d^2 are 60 bored out true to receive the pistons f , which carry at their outer ends the segments F, four of which segments form the circular face-plate, which, when the pistons are forced out, bear against the end of the chain-drum C and force 65 it against the friction-collar G for the purpose of winding the chain H around drum C and throwing on the brakes through lever I and brake-rod J. The lever I has its fulcrum in the bearing i , which bearing is secured to the 70 truck-timber E.

The male friction G is a disk-shaped collar made in two parts, like the drum-cylinder and clutch, and has recessed radial depressions in its concave face to receive radial ribs projecting from the curved flange a of the sleeve A, as seen in dotted line, Fig. 1, to hold the collar G and sleeve A coupled together. The purpose in making the collar G separate from 75 the clutch is to provide for its removal when 80 worn and replacement by a new one. It is obvious, however, that the whole male member of the friction-clutch may be cast as a part of the two-part sleeve.

The pistons are preferably cast with depressions upon their exterior surfaces to receive plumbago plugs, as shown by the rows of black dots, in order to lubricate the surfaces.

In the modification shown in Fig. 5 the pistons f and their segments are made in separate pieces and secured together by screws f' , so that different metals may be used for the pistons and segments, if desired. By thus arranging the friction-clutch and its operating device upon the axle, I avoid all jarring from 90 unequal motion between the parts. The parts are more compact and easier to fit up for use, and the wear in use will be more uniform.

My present invention, like my former one, may be applied to any of the brakes now in common use, the brake-rod J representing the ordinary rod used for connecting the ordinary 5 brake-levers.

What I claim herein is—

1. The combination, substantially as specified, of a sleeve formed in two parts to embrace and be secured to a car-axle, and having 10 one end formed as one member of a friction-clutch, a chain-drum, also formed in two parts, the ends of which are friction-surfaces, an air-cylinder, also formed in two parts, the pistons fitting said cylinder and having face-plate sections, the said drum and cylinder being fitted 15 upon the sleeve and the air-cylinder being held stationary, as shown.

2. An air mechanism for operating a fric-

tion car-brake clutch, consisting of the chambered cylinder D d' and plungers fitting said cylinder, consisting of face-plate sections F and pistons f.

3. The combination, substantially as specified, of sleeve A a, drum C, collar G, cylinder D, sections F, pistons f, chains d and H, and 25 lever I, arranged to operate as set forth.

4. The combination, substantially as herein-before set forth, of air-cylinder D d' d'' and plungers F f, said parts f having their bearing-surfaces inlaid with plumbago, for the purpose 30 set forth.

GEORGE P. CAMPBELL.
